F. WESTERBECK.

BY E. M. Harrington.

UNITED STATES PATENT OFFICE.

FREDERICK WESTERBECK, OF ST. LOUIS, MISSOURI.

CONTAINER.

947,507.

Specification of Letters Patent. Patented Jan. 25, 1910.

Application filed June 12, 1909. Serial No. 501,708.

To all whom it may concern:

Be it known that I, FREDERICK WESTERBECK, a citizen of the United States of America, residing in the city of St. Louis, in the State of Missouri, have invented certain new and useful Improvements in Containers, of which the following is a full, clear, and exact description, reference being had to the accompanying drawings, forming part 10 of this specification.

My invention relates to a container that is more especially intended for use in kitchen cabinets, but which may be used aside from such cabinets, the invention having for its 15 object the production of a container having a bin, a cup slidably mounted beneath the bin and arranged to receive substance discharged therefrom, and means whereby the discharge from the bin may be shut off 20 when the cup is withdrawn from the container and permitted to take place when the cup is introduced into the container.

One of the principal features in my present improvement is the construction whereby 25 the discharge of contents from the bin of the container may be positively stopped in a manner to prevent the entrance of objects descending from the bin acting to clog the discharge opening, with the result of preventing proper closure of the discharge shut 30 off device.

Figure I is a vertical longitudinal section through my container. Fig. II is a vertical cross section through the container, taken 35 on line II—II, Fig. I, the cup being omitted. Fig. III is a horizontal section taken on line III—III, Fig. I, and looking upward, as indicated by the arrow crossing said line, the cup being omitted. Fig. IV is a top or 40 plan view of the cup utilized in my container.

In the accompanying drawings:—1 designates a bin which is provided at its lower end with a hopper shaped bottom 2. 3 designates a housing located beneath the bottom of the bin 1 and attached to said bottom in any suitable manner. This housing is preferably of cylindrical shape, having a flattened top, is closed at its rear end, and has 45 an open forward end. In the top of the housing is a discharge opening 4, through which substance placed in the bin 1 may descend.

50 6 is a guide plate also having a discharge opening registering with the discharge opening 4 in the top of the housing 3 and secured to the top of the housing at its under

side and which is provided with downturned and inturned side flanges 7 that serve to provide slideways within which a shut-off valve 9, to be presently more particularly referred to, is operable. These side flanges 7 are provided intermediate of their ends with shoulders 8. The shut off valve 9 is slidably mounted within and supported by the side flanges 7 of the guide plate 6 and 65 which is adapted to be moved forwardly to close the discharge opening leading from the bin 1 and the discharge opening to the housing 3 and to be moved rearwardly so that said opening will be exposed for the descent 70 of the contents from the bin to the housing and into a cup provided for the reception of such contents, as will hereinafter appear. The valve is provided at its rear end with a depending arm 10 and at its forward end 75 with a depending arm 11, the latter being preferably constructed of a piece of wire bent into a loop, having its arms fastened to the valve and the forward closed end of the loop bent downwardly, as seen most 80 clearly in Fig. I.

12 designates a cup that conforms in shape to and is slidably fitted in the housing 3, this cup being designed to receive contents from the bin 1 of my container and to operate the valve 9, with the result of shifting it to permit the descent of contents from the bin when the cup is introduced into the housing and to move the valve to close the discharge opening when the cup is withdrawn from the housing. The cup is open at its top and the opening is spanned by a valve operating member 13, preferably consisting of a piece of wire bent into T-shape, the head of the T extending across the opening in the cup and the leg of the T extending rearwardly to the back end of the cup 95 to brace the head.

When the cup is introduced into the housing of the container, it being assumed that the valve 9 is at this time in a forward position and closing the discharge opening leading from the bin 1, the rear end of the cup, by striking against the depending arm 10 of the valve, acts to move said valve rearwardly with the result of so shifting it as to permit the descent of contents from the bin into the cup. Then, when the cup is withdrawn from the housing, the valve operating member 13 moves into engagement 105 with the forward depending arm 11 of the valve and the valve is drawn forwardly 110

by said member until it has reached its limit of forward movement, at which time it has effectually closed the discharge opening and the cup may be completely withdrawn from 5 the housing of the container without liability of additional descent of substance from the bin. As the valve reaches its limit of forward movement, its rear depending arm strikes against the shoulders of the guide 10 flanges 7 to prevent the complete withdrawal of the valve.

I will next refer to one of the main features of my present improvement and which 15 contemplates the prevention of objects becoming clogged in the discharge opening of the container upon the closing of the shut off valve in a manner to permit of material descending through said discharge opening at a time that the shut off valve is intended 20 to be in a closed position. By making the discharge opening of circular form, as it is usually made in containers provided with shut off valves, there is opportunity for the descent of a large object into a position in 25 front of the shut off valve as it is closed and which, by preventing complete closure of the valve, permits the presence of spaces alongside of it through which smaller objects may descend at the time that the discharge 30 opening is intended to be wholly obstructed by the shut off valve. Moreover, two or more objects may become wedged in the discharge opening in front of the shut off valve instead of a single large object 35 and the same result occur as in the presence of a single large object, namely, incomplete closure of the discharge opening.

To prevent the objectionable feature of the shut off valve being held from proper 40 closure in the manner referred to, I provide the discharge opening of my housing with a narrow forward extension 5, preferably of tapering or V-shape, as seen in Figs. I and III. By furnishing the discharge opening 45 with this extension, I provide for the shut off valve being moved toward the narrowest end of the extension during the descent of contents from the bin of the container so that discharge of contents may be gradually 50 cut off until only one object may descend

through the discharge opening, and if this one object should become clogged in extension of the discharge opening, it effectually and completely closes the passageway and there is no opportunity for the leakage 55 of other objects alongside of it from the bin of the container, as there would be in any construction other than one involving a narrow passageway, such as that furnished by the extension of my discharge opening. 60

With the object in view of protecting the narrow extension 5 of the discharge opening 4 so that there will be less opportunity for the objects being forcibly pressed into said extension during the closing of the shut off 65 valve, I place above said extension a horizontal box shaped guard 5', (see Fig. I). This guard, by overhanging the extension 5 of the discharge opening, prevents the contents of the bin 1 from being pressed into 70 the extension by the mass of material uppermost in the bin, as will be readily understood.

I claim:—

1. In a container, a bin having a discharge opening, a housing having a discharge opening provided with a tapering extension, a horizontal box shaped guard located above said tapering extension of the discharge opening of the housing, and a shut 75 off valve for controlling said discharge opening of the housing and movable toward said tapering extension.

2. In a container, a bin having a discharge opening, a housing beneath said bin, 80 a cup removably mounted in said housing, a shut off valve for controlling said outlet provided with a depending arm adapted to be engaged by said cup, and guide members attached to said housing in which said shut off valve is operable, the guide members being provided intermediate of their ends with shoulders adapted to be engaged by the depending arm of said shut off valve to limit 85 the movement of the valve.

FREDERICK WESTERBECK.

In the presence of—

Wm. H. SCOTT,
E. B. LINN.
